RADIO RECEIVER

William D. Loughlin, Mountain Lakes, N. J., assignor, by mesne assignments, to Radio Corporation of America, New York, N. Y., a corporation of Delaware

Application December 11, 1933, Serial No. 701,917

18 Claims. (Cl. 250—20)

This invention relates to radio receivers and particularly to receivers which include elements operable automatically to suppress all noise and disturbing output when the receiver is not tuned to some one of a plurality of pre-selected stations.

Receivers of this type are described and claimed in my copending application Serial No. 691,541, filed September 29, 1933, and include, in general, circuit elements for normally suppressing the receiver output, either partially or completely, and a muting switch system operable synchronously with the tuning adjustment for restoring normal operation when the receiver is tuned to one of the selected stations. The switch system preferably includes "indexing" elements which facilitate the tuning to desired stations by yieldingly arresting the tuning control as it reaches a position corresponding to a selected station, and a manually operated switch for rendering the automatic muting system inoperative when it is desired to tune the receiver in the usual manner to any station within the entire operating range.

An object of the present invention is to provide a radio receiver including a simple and efficient muting switch system. An object is to provide a muting switch system which is not associated with the tuning dial of the receiver and which therefore imposes no material restrictions upon the design of the receiver chassis, cabinet or dial member. A further object is to provide a receiver including a muting system having a relatively large space for the location of the adjustable elements which determine the pre-selected frequencies that may be received. A further object is to provide a receiver including a muting system having elements affording an index for facilitating tuning when the muting system is adjusted to receive only the selected favorite stations, and apparatus for rendering the indexing system inoperative when the muting system is adjusted to permit tuning to any station within the operating range of the receiver.

These and other objects and advantages of the invention will be apparent from the following specification when taken with the accompanying drawings, in which,

Fig. 1 is a fragmentary circuit diagram of a radio receiver embodying the invention,

Figs. 2 and 3 are an end elevation and a fragmentary side view, respectively, of a muting switch system mounted on the end of a gang condenser,

Fig. 4 is a side elevation of the switch structure,

Figs. 5 and 6 are fragmentary sections taken on lines 5—5 and 6—6, respectively, of Fig. 2.

Figs. 7 and 8 are enlarged fragmentary sectional views showing alternative adjustments of the switch structure.

Fig. 9 is a fragmentary perspective view of another form of cam and fixed contact plate, and

Figs. 10 to 12 are perspective views illustrating other forms of contact fingers.

The general circuit arrangement and method of operation are indicated in the fragmentary and schematic circuit diagram of a radio receiver, Fig. 1. The receiver may be of any convenient or preferred design and will usually include one or more radio amplifier tubes 1 having tuned input circuits each comprising an inductance 2 and tuning condenser 3. The tube or tubes 1 work into succeeding stages, indicated schematically by the block 4, which include a detector and an audio amplifying system working into a reproducer 5. The succeeding stages may include a tuned circuit, as indicated by the condenser 6, such as a further radio circuit or the local oscillator circuit, and all tuning elements are preferably mechanically connected, as indicated by the broken line 7, to a common shaft 8 that carries or is connected to a tuning knob 9.

In accordance with the invention, a muting switch is mounted on or actuated synchronously with the shaft 8 to control the operation of the receiver. The exact form and location of the muting circuits in which the switch is located are subject to variation to meet different design requirements and, as shown in Fig. 1, the muting system includes a biasing resistor 10 in series with the normal cathode bias resistance 11 of the tube or tubes 1, the resistor 10 being by-passed to ground for radio frequencies by a condenser 12. The muting switch includes a fixed contact 13 connected to the cathode terminal of the resistor 10, and a plurality of contact fingers 14 that are mounted on the shaft 8 and connected to ground. The resistor 10 is of such value as to develop a heavy bias voltage which blocks or substantially suppresses transmission by the tube or tubes 1 to extinguish or to materially reduce the output of the reproducer 5 when the tuning shaft is so adjusted that the muting switch 13, 14 is open. When the receiver is tuned to a pre-selected station corresponding to the engagement of a contact finger 14 with the fixed contact 13, the resistor 10 is short circuited and normal transmission takes place since the bias voltage developed by the resistor 11 is appropriate for high amplification.

A manually operated switch 15 is preferably con-

nected across resistor 10 to permit normal transmission throughout the entire tuning range when the switch is closed.

As shown in Fig. 2, the switch mechanism is mounted upon a plate 16 which may be, and conveniently is, the end plate of a gang condenser assembly which has a plurality of movable plate sections mounted on a rotor shaft 8. This mounting of the switch mechanism has the advantage that there is no backlash or lost motion between the tuning condenser and the movable switch members. A pair of contacts 13' are mounted upon the opposite flanged ends of an elongated plate 17 which has its apertured center portion in contact with the projecting hub of an annular disk 18, the disk and the plate 17 being both fixed to the plate 16 by screws 19 which are threaded into the plate 16. The plate 17 is resilient and the outer ends of the plate may be forced away from the fixed plate 16 by the cam flanges 20 on a cam plate 21 which is rotatably mounted on the hub of the disk 18, the cam plate being angularly adjustable by a shaft 22 and linkage 23.

As shown in Figs. 7 and 8, insulating strips 24 are provided between the contacts 13' and the plate 17, and the contacts have lugs 15' which extend toward the plate 16 to serve as the movable contacts of a pair of parallel switches. In the usual receiver design, the condenser frame will be grounded on the chassis and the insulated contacts 13' may be connected to the junction of the biasing resistors 10, 11 by leads 24a. Each contact element 13', 15' therefore combines the contacts 13 and 15 of the Fig. 1 circuit into a single element that is manually displaceable, as will be explained later, from position in engagement with the fixed contact or plate 16 into a position in the path of movement of the movable contacts of the muting switch system. Normal transmission through the receiver is possible only when the contact element 13', 15' engages either the fixed contact 16 or one of the contacts 14'.

The several contact fingers 14' are adjustably mounted on a disk 25 which is secured to the projecting end of the rotor shaft 8, the parts preferably having mating non-circular portions to prevent relative rotation of the disk and shaft. The hubs of the contact fingers 14' have circular openings to permit their angular adjustment on the shaft 8, and the fingers are clamped in desired positions by screws which pass through the fingers and engage nuts 26 that have flattened portions extending into the arcuate slots 27 of the disk 25. The slots 27 have an angular extent of almost 360° and therefore provide a correspondingly wide range of adjustment for the contact fingers. Although the range of adjustment of the tuning condenser is usually about 180°, the fingers 14' may be positioned over twice that range since there are two diametrically opposed contacts 13' which cooperate with the contact fingers. This construction is particularly advantageous as two contact fingers at opposite sides of the disk 25 may be set in positions corresponding to adjacent or closely adjacent channels. The two bridge pieces 27' are so arranged that one slot 27 has an angular extent of somewhat more than 180°, thus permitting the location of contact fingers over the full range of tuning adjustment of the gang condenser. As indicated at the left side of Fig. 2, the center lines and therefore the operative positions of two contact fingers 14' at opposite sides of the disk 25 may be displaced by an angle α which is

less than the angular displacement which is possible between adjacent contact fingers.

As is shown in Figs. 4 and 7, the axial spacing of the disk 25 and the contact-carrying plate 17 is such that the contact fingers 14' do not engage the ends of the plate 17 or the contacts 13' when the cam plate 21 is so adjusted that the contacts 15' engage the plate 16. With this adjustment of the parts, the receiver may be tuned in the usual manner over its full operating range. When the cam plate is adjusted to flex the ends of the plate 17 away from the fixed end plate 16, the contacts 13' are moved outwardly into the path of the contact fingers 14', and the switches 15', 16 are opened to include the resistor 10 in the cathode circuit of the tube or tubes 1. With this adjustment there will be little or no output from the reproducer 5 unless the tuning condenser is set to some one of the pre-selected positions corresponding to an engagement of one of the contact fingers 14' with its cooperating contact 13'.

As shown in Fig. 3, the flanged ends of the plate 17 are centrally notched and the edges are rounded to permit the ends of the fingers 14' to ride smoothly up the edge and drop into the central notch as the shaft 8 is rotated. The contact 13' has a V-shaped notch to receive and accurately center the tip of a finger 14' which drops into the notch of the plate 17. The flexed tips of the resilient fingers provide a reliable contact engagement with the contacts 13', thus avoiding the noisy operation which would result from a contact of varying resistance in a biasing circuit. The notched construction of the contacts 13' and the supporting plate 17 provides an indexing action which facilitates tuning to the pre-selected favorite station. This indexing action does not take place, however, when the cam plate 21 is adjusted to engage the contacts 15' with the plate 16.

As indicated above, the notched edges of the contacts 13' act as guides to center the contact fingers 14' in one definite position, and the shapes of the notches in each contact 13' and the plate 17 are so related that the cooperating contacts are in electrical engagement only when the finger 14' is accurately centered in the groove. The receiver therefore tunes sharply to each of the pre-selected stations when the muting system is used. By initially adjusting the contact fingers to positions corresponding to accurate tuning to resonance at the desired frequencies, the operator is assured of accurate tuning, and therefore of good quality reception, whenever a station is brought in by the automatic muting switch system.

As shown in Fig. 9, the angular throw of the cam plate may be reduced by providing a pair of cams 20' for cooperation with each end of the plate 17, one cam of each pair entering a slot 27 in one end adjustment of the cams. The double cam construction has the further advantage that the plate 17 is not warped transversely when the ends are flexed by forcing the cams between the plate and the annular disk 18.

There is considerable latitude in the design of the switch elements and Figs. 10-12 illustrate alternative constructions of the contact fingers. The contact portions of all contact fingers may be conveniently made of identical size and shape by riveting short sections 28 of extruded bar material to resilient fingers 14a. The contacts 28 are preferably of brass, bronze or like materials which may be readily extruded and which have good

electrical properties, while the fingers 14a may be of spring steel. Another type of rounded contact tip 29 may be formed by stamping the flared end of a contact finger 14b into U-shape.

5 While the double contacts 13' and 15' are preferably used to extend the adjustment range of the contact fingers and to obtain greater reliability in the shorting of the muting resistor 10 when full range tuning is desired, it will be apparent that some advantages of the invention may be obtained when only one contact element 13', 15' is employed. This and other changes which may be made in the electrical and physical construction of embodiments of the invention 10 fall within the spirit of my invention as set forth in the following claims.

I claim:

1. A radio receiver of the type including a tuning system, a switch system for rendering said 20 receiver operative only when said tuning system is adjusted for the reception of signals of one of a plurality of predetermined frequencies, said switch system including indexing means providing a mechanical indication of those settings of the tuning system which correspond to adjustments to the pre-selected frequencies, and a manually controlled switch for rendering said receiver operative throughout the entire frequency range of said tuning system, characterized by 25 the fact that means is provided to render said indexing means inoperative when said manually controlled switch is positioned for full-range operation of said receiver.

2. A radio receiver as claimed in claim 1, 30 wherein said last means is mechanically connected to said manually controlled switch for operation simultaneously therewith.

3. In a radio receiver, the combination with 35 adjustable means for tuning the receiver over a frequency range, a detector, a reproducer, and means for preventing the overall transmission of signals through said receiver and reproducer, of switch means for rendering said transmission-preventing means inoperative, said switch means 40 comprising cooperating contact means in the form of a contact and a plurality of contact members, means connecting one of said contact means to said adjustable tuning means for operation synchronously therewith, and means for 45 displacing one of said means into and out of alternate positions which permit and which prevent, respectively, the engagement of said contact means during the movement of that contact means which is connected to said adjustable tuning means.

55 4. A radio receiver as claimed in claim 3, wherein said plurality of contact members comprise that contact means which is mechanically connected to said tuning means.

60 5. A radio receiver as claimed in claim 3, wherein said contact comprises that means which is displaceable to prevent engagement of said contact means.

6. A radio receiver comprising a radio amplifier 65 including rotatable adjustable means for tuning the same over a frequency range, the tuning means adjustment being complete within substantially 180° rotation of the adjustable means, a detector, a reproducer, and a muting system for 70 controlling the overall transmission through the receiver, said muting system including a contact-carrying member rotatable synchronously with the adjustment of said tuning means, a plurality of contact fingers adjustably mounted on said member, and a pair of relatively fixed contacts at

opposite sides of the axis of rotation of said member, the said contact fingers being secured in positions on said member which bring the same severally into engagement with one or the other of said fixed contacts when said tuning means is 75 adjusted to positions corresponding to certain predetermined frequencies, said contact fingers being resilient and said fixed contacts are notched to provide an indexing action, in combination with means for simultaneously displacing both of 10 said fixed contacts to positions outside the path of movement of said contact fingers.

7. In a radio receiver of the automatic muting type, an amplifier and means for tuning the same over a frequency range, a detector working into 15 an audio amplifier and reproducer, and means including a muting switch system for controlling the overall transmission of said receiver; said muting switch system comprising a relatively fixed contact-carrying member of resilient material, a contact element secured to and insulated from said member, a rotatable contact-carrying member, a plurality of contact members adjustably secured to said rotatable member, and manually operated means for flexing said relatively 20 fixed member to move said contact element into and out of the path of movement of said contact members.

8. A radio receiver as claimed in claim 7, in combination with a fixed means having the same 30 electrical potential as said contact members, said fixed means being positioned to be engaged by said contact element when the latter is positioned outside of the path of movement of said contact elements.

9. In a radio receiver, the combination with an 35 adjustable tuning element and a network having a pair of terminals which must be electrically connected to place the receiver in operating condition, of means for connecting the said terminals; said means comprising a disk member rotatable synchronously with the adjustment of said tuning element, a resilient plate having a flanged end located adjacent the periphery of said disk 40 member and with the flanged end substantially parallel to the axis about which said disk member may be rotated, a contact element secured to and insulated from said flanged end, a plurality of contacts mounted on said disk member for engagement with said contact element, said plate normally positioning said contact element outside the path of movement of said contacts, and cam means operable to flex the said plate to displace 45 said contact element into the path of movement 50 of said contacts.

10. In a radio receiver of the muting type, a radio amplifier and adjustable means for tuning the same, a fixed plate, a shaft extending through said plate and rotatable synchronously with the 60 adjustment of said tuning means, a disk on said shaft and carrying a plurality of contacts, a resilient member having a portion secured to said fixed plate and another portion carrying a contact element, and cam means for flexing said resilient member to move said contact element into alternative positions for cooperation alternately with said contacts and with said fixed plate to complete an electrical circuit.

11. A receiver as claimed in claim 10, wherein 70 the range of adjustment of said tuning member corresponds to a maximum angular adjustment of said shaft of not more than 180°, and said resilient member carries a second contact element which is spaced from said first contact element 75

by an angle substantially equal to the said maximum angular adjustment of said shaft.

12. A radio receiver comprising a tunable amplifier including an adjustable condenser assembly having end plates and a shaft extending beyond both end plates, a disk member secured to a projecting end of said shaft, a plurality of contacts adjustably secured to said disk member, a resilient member secured to the end plate adjacent said disk member, contact means carried by and insulated from said resilient member for cooperation with said contacts, and cam means for flexing said resilient member to displace said contact means into and out of the path of movement of said contacts.

13. A receiver as claimed in claim 12, wherein said resilient member has a centrally apertured portion through which the said projecting end of said shaft extends, and a pair of radially extending portions which terminate in flanged ends, and said contact means comprises a contact element secured to each of said flanged ends of the resilient member.

14. A radio receiver as claimed in claim 12,

wherein said contacts comprise resilient contact fingers.

15. A radio receiver as claimed in claim 12, wherein said contacts comprise resilient contact fingers having the contact ends thereof bent into U-shape.

16. A radio receiver as claimed in claim 12, wherein said contacts comprise resilient contact fingers, and contact elements secured to said fingers.

17. A radio receiver as claimed in claim 12, wherein said contacts comprise resilient contact fingers, and contact elements of extruded metal secured to said fingers.

18. A radio receiver as claimed in claim 9, wherein said resilient plate is apertured adjacent said flanged end, and said cam means comprises a cam plate and a pair of cams thereon, one cam projecting through said aperture and the other lying adjacent said resilient plate when said cam plate is adjusted to position said contact element outside the path of movement of said contacts.

WILLIAM D. LOUGHLIN.
